SCULPTURING TOOL

Anne T. Amiot, 18132 Audette,
Dearborn, Mich. 48124

Filed Feb. 26, 1973, Ser. No. 336,035

Term of patent 14 years

Int. Cl. D19—06

U.S. Cl. D8—14

FIG. 3

FIG. 8

FIG.1

FIG.2

FIG.6

FIG.5

FIG.4

FIG.7

FIG. 1 is a front elevational view of a sculpturing tool of my present design;

FIG. 2 is a view of a sculpturing tool of FIG. 1 as seen from line 2—2 thereof;

FIG. 3 is a view as seen from line 3—3 of FIG. 2;

FIG. 4 is a view seen from line 4—4 of FIG. 2;

FIG. 5 is a view similar to FIG. 1 illustrating another embodiment of my sculpturing tool;

FIG. 6 is a view as seen from line 6—6 of FIG. 5;

FIG. 7 is a view as seen from line 7—7 of FIG. 6; and

FIG. 8 is a view as seen from line 8—8 of FIG. 5.
I claim:

The ornamental design for a sculpturing tool, as shown and described.
